Patented Feb. 27, 1917.

UNITED STATES PATENT OFFICE.

JOHN M. FEDDERS, OF BUFFALO, NEW YORK, ASSIGNOR TO FEDDERS MANUFACTURING COMPANY, INC., OF BUFFALO, NEW YORK, A CORPORATION OF NEW YORK.

RADIATOR FOR AUTOMOBILES.

1,217,732.

Specification of Letters Patent.

Patented Feb. 27, 1917.

Application filed September 18, 1915. Serial No. 51,374.

To all whom it may concern:

Be it known that I, JOHN M. FEDDERS, a citizen of the United States, residing at Buffalo, in the county of Erie and State of New York, have invented new and useful Improvements in Radiators for Automobiles, of which the following is a specification.

In radiators for automobiles and the like as heretofore constructed a considerable amount of water was liable to be lost through the vent or overflow pipe as the automobile tossed about in passing over rough roads and caused the water to splash into the overflow pipe, thereby necessitating unduly frequent refilling of the radiator in order to maintain the same in an efficient condition.

It is the object of this invention to provide a radiator with guard devices which will permit of readily refilling the same with water and also maintain an uninterrupted communication between the interior and the exterior of the radiator without permitting any of the water in the radiator to splash into and escape through the vent and overflow pipe.

In the accompanying drawings: Figure 1 is a fragmentary vertical section of the upper part of an automobile radiator provided with my improvements. Fig. 2 is a horizontal section taken in line 2—2, Fig. 1. Fig. 3 is a detached side elevation for the guard of the filling tube. Fig. 4 is a perspective view of the guard for the vent and overflow pipe.

Similar characters of reference indicate corresponding parts throughout the several views.

My improvements are applicable to various forms of radiators for automobiles and the like, that shown in the drawings for example, comprising an upper water header or box 1, a filling tube 2 projecting upwardly from the top of this header and communicating at its lower end with the interior of the same, a cover 3 for the upper end of the filling tube which is detachably connected with the latter by means of an annular depending flange 4 forming part of the cover and having an external screw thread which engages with an internal screw thread in the upper end of the filling tube, and a vent or overflow pipe 5 having its upper or inlet end arranged vertically within the fill-

ing tube on one side thereof while its lower end extends to the exterior of the radiator. Water may be added to the radiator from time to time by removing the cover and pouring the water through the filling tube 60 into the upper header. Any surplus water enters the upper end of the overflow pipe 5 and escapes at the lower end thereof to the exterior of the radiator and any steam which is generated within the radiator by the heat 65 from the engine also escapes to the exterior through this pipe which at this time serves as a vent for this purpose.

For the purpose of preventing the water while being agitated in the radiator during the passage of the automobile over rough roads from splashing upwardly into the filling tube a guard device is provided for the same which preferably comprises an imperforate body 6 of substantially tubular form 70 arranged vertically within the filling tube and provided on one side with a longitudinal external groove 7 which receives the upper portion of the vent and overflow pipe. At its upper end this imperforate tubular 80 body is provided with a laterally projecting supporting flange 8 which is normally clamped between an upwardly facing internal shoulder 9 formed in the bore of the filling tube and the lower end of the cover 85 flange, as shown in Fig. 1. This flange of the filling tube guard is also provided with an opening 10 which receives the upper end of the vent and overflow pipe. At its lower end the body 6 is provided with a screen 11 90 extending horizontally across the same which screen is preferably constructed of woven wire although the same may be constructed in any other suitable manner.

As the water in the header or body is 95 agitated or splashed the same strikes the imperforate tubular body of the guard device for the filling tube and is therefore prevented from splashing into the upper part of this tube while at the same time free communication is maintained in the upper part of the filling tube and the interior of the header through the medium of the screen 11 which latter permits water to be poured from the filling tube into the handle and also permits the water to rise and fall normally within the body of the filling tube guard.

In order to prevent any water from splashing into the upper end of the vent and overflow pipe and thus become wasted a 110

2

guard device for this pipe is provided which is preferably constructed in the form of a cap 12 which fits over the upper end of the vent and overflow pipe and forms therewith 5 passages 13 which place the interior of the water header in communication with the vent and overflow pipe. These passages are preferably formed by providing the cylindrical body of the vent and overflow guard 10 with longitudinal beads 14 which are bent inwardly and engage with the exterior of the vent and overflow pipe, and traverse beads 15 which are bent downwardly in the top of this last mentioned guard and engage 15 with the upper end of the vent and overflow pipe, as shown in Figs. 1 and 2. This vent and overflow guard is held in place frictionally on the pipe 5 so that the same may be readily removed when necessary for inspection, cleaning and repairs, and in its 20 normal operative position the lower part of this guard extends downwardly through the opening 10 on the flange of the filling tube 5 into the vent and overflow pipe is guard, so that the vent and overflow pipe is 25 not in direct communication with the upper end of the filling tube but more directly in communication with the upper end or top of the water box or header.

It will be evident from the foregoing explanation that by means of my improvements it is practically impossible for any of the water in the radiator to escape through the vent and overflow pipe no matter how violently it is churned or tossed about in 35 the radiator, thereby necessitating less frequent replenishing of the water, this being particularly desirable when the automobile is traveling over a long stretch of bad roads and water is not conveniently available.

40 I claim as my invention:

1. A radiator for automobiles and the like comprising a water header or box provided with an upright filling tube having an up-

wardly facing internal shoulder, a cover for closing said filling tube having a depending 45 flange which is connected by a screw joint with the inner side of said tube and has its lower end facing said shoulder, a vent and overflow pipe arranged within said tube on one side thereof, and a guard for said tube 50 comprising an imperforate tubular body arranged upright within said tube and provided on one side with an external longitudinal groove which receives said pipe, a laterally projecting flange at the upper end of 55 said body which is clamped between said shoulder and the cover and which is provided with an opening for the passage of said pipe and a screen arranged across the lower end of said body. 60

2. A radiator for automobiles and the like comprising a water header or box provided with an upwardly projecting filling tube, a closure for the upper end of said tube, a vent and overflow pipe projecting upwardly 65 into said filling tube and a guard for said pipe comprising a cap fitting over the upper end of said pipe and constructed to form internal passages leading from the lower end of said cap to the upper end of said pipe. 70

3. A radiator for automobiles and the like comprising a water header or box provided with an upwardly projecting filling tube, a closure for the upper end of said tube, a vent and overflow pipe projecting upwardly into 75 said filling tube, and a guard for said pipe comprising a cap arranged on said pipe and having its side provided with inwardly bent longitudinal beads which engage with the outer side of said pipe and its top provided 80 with downwardly bent beads which engage with the upper end of said pipe and form passages between said cap and pipe leading from the lower end of the cap to the upper end of said pipe. 70

JOHN M. FEDDERS.
